HOWARD R. SARGENT, OF BRIDGEPORT, CONNECTICUT.

INDICATING DEVICE.

Application filed December 31, 1921. Serial No. 526,366.

This invention relates to indicating systems, such as a system for indicating the presence or absence of an employee from his place of work, or for indicating a vacant seat in theatres or the like, or for indicating engaged or vacant rooms in hotels. This invention also relates to indicating devices, and more particularly to such devices for use in factories, theatres, hotels and similar places. Hereinafter I will describe my invention with reference to means for indicating the absence of employees from their place of work. However, it will readily be apparent how the invention may be utilized in connection with hotels, or theatres, or for other like purposes.

The present time clock system employed for indicating and registering the presence or absence of an employee comprises a rack in which individual cards for each employee are retained separately. When an employee leaves his place of work he removes his individual card from the rack, stamps it in the time clock, and then restores the card into its compartment with the reverse side of the card presented outwardly. Then, when the employee returns to his place of employment, he again removes his card from the rack, stamps it in the time clock, and returns it to its compartment with the front face of the card outwardly. This side of the card outward in the rack indicates the presence of the employee and the reverse side of the card outward in the rack indicates the absence of the employee. Under the present time clock system the sole visible indication of the presence or absence of an employee is effected by the position of his or her card in the card rack of the time clock. This rack is usually placed in a hallway or vestibule and is only examined occasionally for information of the presence or absence of an employee. Moreover, if these cards are examined at all, they are examined by the head of the department, or some delegated person, some considerable time after the employee has registered his incoming and outgoing times thereon, and no attempt is made to give indication at any place other than at the card rack of the leaving or of the arrival of the employees. Thus, unless someone is watching, an employee leaves with the feeling that his absence will not be detected until some later time, if at all. If, in addition to this visi-

ble indication on the card rack, visible indication is also given in the office of the head of the department, or in the office of someone delegated by the head of the department, as to when the several employes came in and when they left the place of employment, the moral effect on the employes, who would know that there was a visible record of their movements in the head office, would lead the employes to keep better working hours. Then the employe would not feel upon leaving that the fact would not be detected, but, on the contrary, would feel that his or her leaving was not only immediately detected but also that the indication of absence would be continually before his superior until his or her return.

One of the objects of my invention is to provide a system for indicating the presence and absence of employes, individually, by visibly indicating such facts at a card rack, placed in some suitable location, as adjacent a time clock, and simultaneously and automatically visibly indicating such facts at a place removed from such card rack, as, for instance, in the office where visible indication is desired of the presence or absence of the employes whose cards are harbored in the rack. Another object of my invention is to provide an electrically operated indicating device adapted to be actuated by means of the movement of a card into or out of a compartment therefor in a card rack, and a device which is adapted to register differently according to different predetermined positions of the card in its compartment, so that visible indication of the presence or absence of an employe is simultaneously given at both the card rack and at the indicator. Other objects will be in part obvious and in part pointed out hereinafter.

In accordance with my invention, I place electrically operated indicating devices in the desired office where visible indication of the presence or absence of the employes is desired. I provide an indicating device for each employe, the plurality of devices being preferably contained in a single cabinet and actuated by a common source of current. Each of these devices is adapted to register "In" or "Out", preferably by movement of a target into one position or another, to indicate the presence or absence of the employe to whom the device is allotted. I arrange an electric circuit for operating the

indicating devices and connect this circuit with electrical terminals harbored in the compartments of a card rack, which may be a rack such as is used in connection with 5 time clocks, and place one set of terminals for an indicating device in each compartment. I arrange electrical contacts on a card, such as the standard card, which is intended to be placed in its compartment in 10 one position to indicate that the employe is "in" and to be placed in another position in the compartment to indicate that the employe is "out". I arrange each indicating device, the circuit, the terminals in the corresponding compartment, and the contacts 15 on the corresponding card, in such a way that when the card is removed from the rack and replaced therein with the "in" side of the card presented outwardly the electrical 20 indicator will register "In", and that whenever the card is removed from the rack and then replaced with its "Out" face presented outwardly, the electrical indicator will register "Out." The indicator is arranged to 25 remain set continuously at "In" or "Out" so long as the card remains in the rack in the corresponding position. The card rack may be placed in any desired locality such as in a hallway or vestibule, and removed from the 30 place or office where the electrical indicator is placed. The card rack may comprise the card rack of a time clock system.

Formerly, in order to ascertain if a certain employe was "in" or "out", it was necessary to go to the card rack and ascertain 35 this fact by an examination of the cards. By my improved system the presence or absence of an employe can be ascertained by merely looking at the electrical indicator and 40 thus my system and apparatus obviates the necessity of examining the cards in the rack, although the same information may also be ascertained in this way, if desired.

In order that a clearer understanding of my invention may be had, attention is hereby 45 directed to the accompanying drawings forming a part of this application and showing one of various possible embodiments of my invention. In the drawings, Fig. 1 is a 50 diagrammatic representation of my invention, including a card rack with cards therein, electrical contacts on certain cards, electrical terminals in certain of said compartments, and an indicator, the parts being 55 shown broken away to more clearly bring out certain features of the mechanism; Fig. 1; Fig. 2 is a vertical section of a part of the card 60 rack and is taken on the line 2—2 of Fig. 1; Fig. 3 is a sectional view taken on the line 65 3—3 of Fig. 2; Fig. 4 is a front plan view of a card embodying my invention; Fig. 5 is a rear plan view of the card illustrated in Fig. 4; and Fig. 6 is a fragmentary view in 70 section of the card showing the electrical 75 contact piece mounted thereon.

Referring to the drawings, the card rack 1 is provided with a plurality of compartments 2, each compartment being adapted to harbor a card 3. The card rack compartments and cards may be of a well known 70 type and may suitably comprise a card rack and cards such as are employed in connection with time clock systems. Each card has its obverse face marked with the name of an employe and also preferably with the 75 word "In". The reverse face of the card preferably carries the word "Out". The card is adapted to be placed in its individual compartment with the face marked "In" presented to view when the employe arrives 80 at his place of employment, and the card is adapted to be removed from the compartment and placed therein with the reverse face presented outwardly when the employe leaves the place. Usually, proper records 85 of the time of leaving and returning are placed upon the card as by printing the same in a time clock. This printing operation, however, forms no part of my invention. 90

I provide two pairs of electrical terminals in each compartment. As shown, one pair of terminals comprises two resilient strips of metal 4 and 5 fastened to a frame member 6 of the card rack 1 by means of screws 7. 95 The lower end of these terminal strips 4 and 5 are connected in electrical engagement with the ends of conductors 8 and 9 respectively, these conductors being preferably held in place by means of the screws 7. The 100 other pair of each set of terminals is similar to the first pair, and, as shown, comprises two resilient strips of metal 4' and 5' fastened to the frame member 6 of the card rack 1 by means of screws 7'. The lower ends of 105 these terminal strips 4' and 5' are connected in electrical engagement with the ends of conductors 8' and 9' respectively, these conductors being preferably held in place by means of screws 7'. As will be hereinafter 110 described, the making of electrical contact between one pair of these terminals will 115 actuate a suitably located indicating device into one indicating position and the establishment of electrical contact between the other pair of these terminals will actuate 120 said indicating device into another indicating position, such contacts being adapted to be made by the card as it is manipulated in the manner usual to time clock systems. 125

As before pointed out, in order to take advantage of the moral effect on the employes, it is well to place the indicating devices in the office of a superior, but, obviously, the indicating devices may be 125 placed in any desired locality. I preferably provide an indicating device for each compartment of the card rack so that each device will be individual to an employe, though I may, if desired, allot one device to 130

several compartments or employes. These indicating devices may be separately housed in suitable containers or, as shown, several or all may be mounted in one container 10. 5 As shown, the indicating member of each device comprises a target 11 which is movable so as to be presented at either of two windows, 12 and 12', formed in the outer wall of the housing 10. The target is 10 adapted to be presented at one of the windows, such as 12, when the card in the rack signifies that the employe is at the place of employment, and the target is adapted to be presented at the other window, such as 15 12', when the card in the rack indicates that the employe is absent. Accordingly, the first window, 12, may appropriately be labeled "In" as by placing the word "In" on the casing 10, adjacent thereto, as at 32, and 20 the other window 12' may be labeled "Out" as by placing the word "Out" on the casing 10 adjacent thereto, as at 33.

The target 11 is fastened to or formed on the upper end of a lever 21, which is pivotally mounted, as at 22, on the casing 10, or on a support 17, attached thereto. The lower end of lever 21 is pivotally connected, as with a pin and slot connection 20, to the upper end 18 of a lever 19, which is pivoted 30 to the casing 10, or to the support 17, as at 16. Lever 19 carries an armature 15 which is horizontally disposed over the ends of two electro-magnets 13 and 14 in such a way that when magnet 13 is energized 35 the adjacent end of the armature will be tilted downward, and when the magnet 14 is energized the end of the armature adjacent this magnet will be tilted downward. Thus it will be seen that when magnet 13 is energized 40 the armature will be tilted as indicated in dotted lines in Fig. 1, and by reason of the above described connection between the armature and the target 11 this target will be moved to window 12, and 45 when magnet 14 is energized, the armature 15 will be tilted into the position shown in full lines in Fig. 12, and the target will be moved to window 12'. The target 11 is adapted to be held by the action of gravity 50 at either one window or the other until a magnet is energized to cause the target to move to the other window. Each end of the armature 15 is adapted to come to rest on one of the magnets, thereby acting as a 55 stop to hold the target in proper position at the respective windows. Magnets 13 and 14 are suitably supported within the casing 10.

I establish an electrical circuit between 60 one set of the terminals, such as 4 and 5, in a compartment, and one of the magnets, such as 13, and also a circuit between the other set of terminals, 4' and 5', and the other magnet, 14, a battery 23 or other 65 suitable source of current being supplied

in the circuit. As shown, the circuit may be established as follows:—From one pole of the battery 23, a conductor 24 leads to conductors 8 and 8', which are in electrical connection with the terminal piece 4 and 4' 70 in the compartment. The conductor 9 leads from the terminal 5, which opposes the terminal 4, and communicates with the one end of the coil of the magnet 13, and the other end of this coil conductor 25 connects 75 with conductor 26 which leads into the opposite pole of the battery 23. The conductor 9' leads from the terminal 5', which is opposite the terminal 4', to one end of the coil of the magnet 14. The other end of 80 the coil of this magnet is connected by conductor 27 to the conductor 26 which leads into the battery 23.

Each card 3 is supplied with a pair of electrical contacts extending from one face 85 of the card to the other. These contacts may comprise small rivets 28. One of the contacts 29 is placed adjacent an edge of the card, and the other contact 30 is placed toward the center of the card and in staggered relation to the contact 29. The tops of the terminal pieces 4, 4', 5 and 5' are preferably bent over as at 31, and are so arranged that when either contact 29 or contact 30 passes between the portions 31 of a 90 pair of terminals the contact establishes the circuit between such terminals, and actuates either magnet 13 or magnet 14 according to which pair of terminals is bridged by a contact. The contacts 29 and 30 are so placed 95 on the card that when the card is moved into or out of its compartment with its "Out" face presented outwardly, neither contact 29 nor contact 30 will engage or bridge either pair of terminal pieces. 100 When, however, the card is passed into the compartment with the "In" face presented forwardly, first contact 30 is arranged to pass between the terminals 4' and 5', and to bridge the same temporarily to complete the 105 circuit between said terminals, and then, upon further movement of the card inwardly, the contact 29 is arranged to pass between and to bridge both terminals 4 and 5 to temporarily establish electrical contact 110 between these terminals. When the card is finally seated in its compartment, both contacts 29 and 30 will have passed by the engaging portions of the terminals 4, 4', 5 and 5', and no circuit is maintained. Now, 115 when this card is pulled out of its compartment, first contact 29 will establish a circuit between the terminals 4 and 5, and then contact 30 will in passing establish a circuit between the terminals 4' and 5'. It will be 120 readily apparent that whenever contact 29 establishes the circuit between the terminals 4 and 5, magnet 13 is energized, thus causing the target 11 to be thrown toward the right 125 and into view at the window 12, and when- 130

ever contact 30 establishes the circuit between terminals 4' and 5', magnet 14 is energized and thus causes the target to be thrown to the left and into view at the other window, 12'.

The operation of my system is as follows:—The employe upon arriving removes his card from its compartment. If the card is as it should be with the "Out" face outward, this operation will have no effect upon the circuit through the indicating device, since neither contact 29 nor contact 30 will engage either pair of terminals. The employe now stamps his card in the time clock, reverses it, and slides it into its compartment with its "In" face presented outwardly. As the card enters its compartment, in this position, first contact 30, in passing, will establish a temporary circuit between terminals 4' and 5' and through the magnet 14, but if, as it should be, the target 11 is already in its "Out" position no movement of the target will be effected. However, upon further movement of the card into its compartment, contact 29, in passing, establishes a temporary circuit between the terminals 4 and 5. This will energize the magnet 13 for a sufficient length of time to cause the target 11 to move into "In" position. The target will now stay in such position until the magnet 14 is energized. When the employe leaves, he draws the card out of its compartment. During this movement first contact 29, in passing, will again establish a circuit between terminals 4 and 5, but since the target is already in "In" position, no movement of the target 11 will be effected. Upon further withdrawal of the card, contact 30, in passing, will establish a closed circuit between terminals 4' and 5'. This closed circuit energizes the magnet 14 and causes the target 11 to be thrown into its "Out" position. When the card has been removed, it may be stamped in the time clock, if desired. Then, when the card is placed into its compartment with its "Out" face outwardly, neither contact 29 nor contact 30 will engage the terminal pieces in the compartment, and since no circuit is closed, the target 11 will remain in its "Out" position until the card is again inserted in its compartment with its "In" face presented outwardly, and the magnet 13 energized by such movement of the card.

As many changes could be made in the above construction and many apparently widely different embodiments of this invention could be made without departing from the scope thereof, as it is intended that all matter contained in the above description or shown in the accompanying drawings shall be interpreted as illustrative and not in a limiting sense.

What I claim is:—

1. An indicating system of the character

described including a card, a compartment for the card, an electric indicator adapted to maintain the indicating position to which it is actuated, and electrical means, including an electric circuit for the indicator, terminals in said compartment and cooperating contacts on the card, whereby the indicator will be actuated to give certain signals corresponding with the direction of movement of the card, faced in a certain direction, into and out of compartment, and whereby the indicator will not be actuated upon movement of the card, faced in the opposite direction, into and out of the compartment.

2. An indicating system of the character described including a card, a compartment for the card, an electric indicator adapted to maintain the indicating position to which it is actuated, and electrical means, including an electric circuit for the indicator, terminals in said compartment and cooperating contacts on the card, whereby upon movement of the card, faced in a certain direction, into the compartment, the indicator will be actuated momentarily during this movement of the card to become set in a certain indicating position.

3. An indicating system of the character described including a card, a compartment for the card, an electric indicator adapted to maintain the indicating position to which it is actuated, and electrical means, including an electric circuit for the indicator, terminals in said compartment and cooperating contacts on the card, whereby upon movement of the card, faced in a certain direction, into the compartment, the indicator will be actuated momentarily during this movement of the card to become set in a certain indicating position, said means being inoperative to actuate the indicator when the card is faced in the opposite direction.

4. In an indicating system of the character described, the combination with a card, a compartment therefor, an electric indicator adapted to maintain the indicating position to which it is actuated, and a normally open supply circuit therefor; of means, including a contact movable with said card, for momentarily closing said circuit upon movement of the card, faced in a predetermined direction, into the compartment, to actuate the indicating device to give a certain signal, but not closing said circuit upon movement of the card, when faced in the reverse direction, into the compartment.

5. In an indicating system of the character described, the combination with a card, a compartment therefor, an electric indicator adapted to maintain the indicating position to which it is actuated, and a normally open supply circuit therefor; of

means, including a contact movable with said card, for momentarily closing said circuit upon movement of the card, faced in a predetermined direction, into the compartment, to actuate the indicating device to give a certain signal, but not closing said circuit upon movement of the card, when faced in the reverse direction, into the compartment, and for momentarily closing said circuit upon movement of the card, faced in a predetermined direction, out of the compartment, to actuate the indicating device to give a certain signal, but not closing said circuit upon movement of the card, when faced in the reverse direction, out of the compartment.

6. In an indicating system of the character described, the combination with a card, a compartment therefor, an electric indicator adapted to maintain the indicating position to which it is actuated, and a normally open supply circuit therefor; of means, including a contact carried on the card off the vertical center line thereof, for momentarily closing said circuit upon each movement of the card into the compartment and during each movement of the card out of the compartment, when the card is faced in a predetermined direction, to actuate the indicating device to give a signal corresponding to the direction of card movement, but not closing said circuit upon any movement of the card, when faced in the reverse direction, into and out of the compartment.

7. In an electric indicating system of the character described, including an indicator adapted to maintain the indicating position to which it is actuated, a card, a compartment therefor, an electric supply circuit having open terminals, and a circuit closing contact on said card: the relative location of the terminals in the compartment and the contact on the card so that the contact will momentarily bridge said terminals to close said circuit and actuate the indicator to give certain signals when the card, facing in a predetermined direction, is placed in and removed from the compartment, and the contact will pass by the terminals without closing the circuit and without actuating the indicator when the card, faced in the reverse direction, is placed in and removed from the compartment.

8. In an electric indicating system of the character described, including an indicator adapted to maintain the indicating position to which it is actuated, a card, a compartment therefor, an electric supply circuit having open terminals, and a circuit closing contact on said card: the location of the terminals in the compartment and the contact on the card the same distance sidewise of the vertical center lines of the compartment and card so that the contact will momentarily bridge said terminals to close

said circuit and actuate the indicator to give certain signals when the card, facing in a predetermined direction, is placed in and removed from the compartment, and the contact will pass by the terminals without closing the circuit and without actuating the indicator when the card, faced in the reverse direction, is placed in and removed from the compartment.

9. In an electric indicating system of the character described, including an indicator adapted to maintain the indicating position to which it is actuated, a card, a compartment therefor, an electric circuit having open terminals and circuit closing contacts on said card: the location of the terminals in the compartment and the contact on the card the same distance sidewise of the vertical center lines of the compartment and card and at different distances from the bottom edges thereof, so that when the card, facing in a predetermined direction, is placed in and removed from the compartment, the contact and terminals will coact during such movements to momentarily close said circuit to actuate the indicating device to give signals corresponding to the direction of card movement, and so that when the card, faced in the reverse direction, is placed in and removed from the compartment, said contact and terminals will not coact during such movements to close said circuit, and the indicator will not be actuated.

10. In an electric indicating system of the character described, in combination, an indicator adapted to maintain the indicating position to which it is actuated, a card, a compartment therefor, an electric circuit having two pairs of terminals in said compartment, and two-circuit closing contacts on said card; said pairs of terminals being located at different heights in the compartment and at different distances from the side edges thereof, and said contacts having the same relative positions on the card as the pairs of terminals have in the compartment, whereby, when said card, faced in a predetermined direction, is placed in and removed from said compartment, said contacts coact with said pairs of terminals successively to momentarily close said circuit twice in succession during each of said movements to actuate the indicator to give signals corresponding to the direction of card movement, and whereby, when said card, faced in the reverse direction, is placed in and removed from the compartment, neither contact coacts with either pair of terminals to close said circuit, and the indicator will not be actuated.

11. In an indicating system of the character described, the combination with a card and a compartment therefor, of an electrical indicator adapted to maintain the indicating

position to which it is actuated, an electrical supply circuit for said indicator, means movable with said card and operating momentarily during movement of said card into 5 said compartment for momentarily closing said circuit to actuate said indicator into one indicating position and operating momentarily during removal of said card from said compartment for momentarily closing 10 said circuit to actuate said indicator into another indicating position.

12. In an indicating system of the character described, the combination with a rack having a compartment for a card, of an electrically operated indicator, a card movable into and out of said compartment in either 15 one of two different positions and electrical means including terminals and terminal closing contacts responsive to movement of said 20 card for actuating said indicator to give different signals, depending upon which one of the two different positions the card is in when it is inserted into or removed from the compartment.

13. In an indicating system of the character described, the combination with a card and a compartment therefor, of an electrically operated indicator adapted to maintain the indicating position to which it is actuated, two pairs of electrical terminals in said 25 compartment, a card having two electrical contacts constituting means whereby when the card is inserted into said compartment in a predetermined position, first one of said 30 contacts temporarily establishes an electrical connection between one pair of terminals, and upon further movement of said card into said compartment, said other contact temporarily establishes an electrical connection 35 between the other pair of terminals, and elec- 40

trical means whereby said connection between one pair of terminals operates said indicator into one position, and means whereby said connection between said other pair of terminals operates said indicator into another position, said contact means permitting the insertion into or removal from the compartment of the card in another predetermined position without establishing an electrical connection between either pair 50 of terminals.

14. In an indicating system of the character described, in combination, an indicator comprising a movable target, means comprising an electro-magnet for moving said target into one indicating position, and means comprising a second electro-magnet for moving said target into another indicating position and means for maintaining said target in the position into which it is moved, a compartment for a card, an electric circuit for actuating one of said magnets and including a pair of terminals in said compartment, an electric circuit for actuating the second electro-magnet, including the second pair of terminals in said compartment, a card having a pair of contacts so arranged thereon that when the card is inserted into or removed from said compartment in one position, said contacts will successively and temporarily establish the circuits between the terminals of each pair to actuate said indicator, said card being adapted to be inserted into or removed from said compartment in another position without establishing either of said circuits.

This specification signed and witnessed this 22nd day of December, 1921.

HOWARD R. SARGENT.
